CHUTE INTAKE DOOR OR HOPPER

Clarence M. Wilkinson, Akron, Ohio

Application November 16, 1950, Serial No. 196,034

5 Claims. (Cl. 193—34)

1

My invention relates to an intake door or hopper for rubbish or the like for use in combination with a chute or other receptacle, and, more particularly, to an assembly of interlocking doors for a rubbish intake hopper.

Heretofore, it has been proposed to provide a hopper door for receiving rubbish into a chute or other receptacle having spaced-apart doors forming an intermediate space with interlocking means whereby one door is closed while the other is opened so that no direct opening is afforded to cause back drafts between the outside and inside of the receptacle. However, all of such designs of which I am aware are subject to one or more of the following limitations—they are bulky, employ a complicated interlocking linkage, are expensive to manufacture, difficult to install, or are not sufficiently rugged to withstand the dirt and abuse to which they are subjected in use, and, thus, require constant maintenance care.

It is the general object of my invention to avoid and overcome the foregoing and other difficulties of and objections to prior art practices by the provision of an improved chute intake hopper of the double interlocking door type which can be manufactured as a unit with a minimum of parts, and which is rugged and substantially fool-proof in its construction.

Another object of my invention is to provide a rubbish hopper, which is adapted to communicate with a chute or receptacle, having a baffle door which remains locked until the hopper door is completely closed, thereby insuring no back draft.

The aforesaid objects of my invention, and other objects which will become apparent as the description proceeds, are achieved by providing an intake hopper for rubbish or the like in combination with a chute or other receptacle comprising a rectangular frame adapted to be mounted in a wall adjacent the chute, a hood secured to the inner edge of the frame and extending into the chute, a hopper door hingedly secured to the frame along the lower edge thereof, a baffle door hingedly secured along its upper edge to the hood in spaced-apart relation to the hopper door, means interlocking the doors and offset laterally therefrom and including a plate pivotally secured to the hood and having slots diametrically opposed adjacent the peripheral edge thereof, manually operated means for rotating the cam plate, a crank arm secured to each door, a link pivotally secured to each crank arm and slidably engaging the slots in the cam plate, a spring urging the hopper door into closed position, and a

2

locking link pivotally secured to the baffle door crank arm and releasably engaging the cam plate whereby the baffle door is held locked against movement except by proper rotation of the cam plate.

For a better understanding of the invention, reference should be had to the accompanying drawings, wherein:

Fig. 1 is a transverse cross-sectional view of my invention taken substantially on line I—I of Fig. 5 and showing the cam plate and its associated handle in the neutral position wherein both the hopper door and baffle door are closed;

Fig. 2 is a transverse cross-sectional view taken substantially on line I—I of Fig. 5 showing the position of the cam plate and handle when the hopper door is open and the baffle door is closed;

Fig. 3 is a transverse cross-sectional view similar to Fig. 2 but showing the position of the cam plate and associated handle when the baffle door is open;

Fig. 4 is a front elevational view of my invention; and

Fig. 5 is a plan view showing the relative position of the handle and closure mechanism with the hopper door.

With specific reference to the form of the invention illustrated in the drawings, the numeral 10 indicates generally the rubbish hopper assembly which is, in the usual application of the invention, mounted in an opening 12 through the wall 14 adjacent the chute 23. The assembly 10 is supported by means of a rectangular frame 16 having an outwardly extending flange 18 which overlaps the wall 14 around the edge of the hole 12 and is secured in place as by a plurality of screws 20. A vertical bar or channel 19 (see Fig. 5) connects the top and bottom of the frame parallel to one side, the bar 19 dividing the frame into a door area and a control mechanism area. Riveted or otherwise secured to the inwardly extending flange of the frame 16 is a sheet metal hood 22 which extends from the door area of the frame as just described to the chute 23 or receptacle adjacent the back of the wall 14. More specifically, the hood 22 extends along the left side and top of the frame 16 and down along the bar 19. A molding 24 fits over and around the frame 16 to form a finished trim with the wall. The bottom 26 of the assembly 10 is welded or otherwise secured to the frame 16 at 28 between the bar 19 and the left side of the frame and slopes inwardly and downwardly to direct the rubbish into the chute. The sides of the hood 22 are extended down and connect to the bottom 26,

as will be understood, to form a complete guide for any rubbish or other material being passed to the chute 23.

Journaled in holes 30 at the bottom of the in-turned flange of the rectangular frame 16 is the shaft 32, to which the hopper door 34 is securely fastened by welding or similar means. The hopper door 34, shown in its closed position in Fig. 1, abuts along its upper edge against an angle stop bracket 36.

Hingedly secured by means of a shaft 38 in bearings 40, supported by a pair of bars 42 welded to the frame 16, is the baffle door 44. The supporting bars 42, in the preferred embodiment of the invention, are formed out of bar stock and are welded respectively to the rectangular frame 16 and to the bar 19.

To provide manual operation and an interlocking connection between the hopper door 34 and the baffle door 44, mechanism is provided in a box 43 mounted at the side of the hood 22 but within the frame 16 to the right of the bar 19. This mechanism includes a cam or plate 46, having a handle 48 secured thereto and projecting out through a slot 45 beyond the front of a cover plate 47 for the mechanism area. The cam plate 46 is pivotally secured on a shaft 50 journaled in bearings 52, one of which is supported by a bar 53 mounted on the frame 16, and another being carried by a second bar 53 secured to bar 19. Adjacent the peripheral edge of the cam plate 46 and in diametrically opposed position are the arcuate slots 54 and 56 in which the bolts 58 and 60 are slidably engaged to provide lost motion means as hereinafter described.

Rigidly attached to the portion of the shaft 32 extending into the box 43 and to one side of the hopper door 34 is the crank arm 62. A link 64 operatively connects the crank arm 62 with the cam plate 46. The link 64 is pivotally secured to the arm 62 at 56 by appropriate means such as a shoulder bolt and associated threaded nut, and in slot 54 link 64 is similarly pivoted by bolt 58. In the same manner, a crank arm 68 is rigidly secured adjacent the end of the shaft 38 carrying the baffle door 44, and is operatively associated with the cam plate 46 through the link 70 pivotally secured to the crank arm by bolt means at 72 and to the cam plate by bolt 69.

To urge the hopper door 34 closed, a tension spring 74 is employed, secured at one end to the bolt 58 and anchored at the other end by means of an adjustable eye-bolt 76. The spring 74 also serves to counterbalance the weight of the hopper door 34. Eye-bolt 76 in turn is anchored to the frame by means of a bracket 78. The bracket 78 has a screw 79 with a lock-nut 81 threadably secured thereto for providing a stop for the open position of the hopper door 34. The link 64 engages the end of the screw 79 when the hopper door is open, as shown in Fig. 2.

To positively lock the baffle door 44 in closed position when the handle 48 is in neutral position or when the hopper door 34 is open, a locking link 80, pivotally secured to the crank arm 68, is provided having a notch 82 which engages the shaft 50 under the action of gravity when the baffle door 44 is in closed position. To effect disengagement of the notch 82 from the shaft 50 when it is desired to open the baffle door 44, a pin 84 secured to the cam plate 46 is so positioned that as the handle 48 is pushed downwardly rotating the cam plate 46, the pin 84 engages the locking link 80 and moves it out of locking position.

In operation, the handle 48 has three normal positions. The first, illustrated in Fig. 1, is the neutral position in which both the hopper door and baffle door are closed, and the locking link 80 is in engaging position to secure the baffle door 44 in closed position. When the handle 48 is moved upwardly, as shown in Fig. 2, the cam plate 46 rotates through a clockwise angle, the end of the slot 54 engaging the bolt 58, and through link 64 operates the crank arm 62 to thereby open the hopper door 34 against the action of the spring 74. The baffle door 44 remains closed and locked as the bolt 60 slides in the slot 56 and the pin 84 moves away from the link 80. After rubbish or the like is placed in the hopper door 34, the handle 48 is lowered to return it to neutral position, at which time both doors are closed, confining the rubbish within the intervening space. Continued downward movement of the handle 48 by the operator carries it to the lower position as shown in Fig. 3. This rotates the cam plate 46 in a counterclockwise direction, at which time the lower end of the slot 56 engages the bolt 60, thereby lifting the link 70 and by means of crank arm 68, opening the baffle door 44. Simultaneously, as the handle 48 passes through the neutral position, the pin 84 engages the locking link 80 to lift it, thereby disengaging the notch 82 from the shaft 50 to permit the baffle door 44 to swing open as described. After the rubbish slides down the inclined bottom 26 into the chute 23 or receptacle, the handle is merely released and the weight of the baffle door 44 causes the baffle door to close and lock and the handle automatically returns to its neutral position. During the movement of the handle 48 from the neutral position of Fig. 1 to the lower position of Fig. 3, the lost motion connection of slot 54 and bolt 58 allows this without movement of hopper door 34, which is held closed by the spring 74 to prevent back drafts. The strength of the spring 74 is adjusted so that the weight of the hopper door 34 just keeps the hopper door open when in fully open position whereby an operator, if he so desires, can use both hands to deposit rubbish or the like in the hopper. However, once the operator begins to push the handle 48 downward from its uppermost position, the strength of the spring 74 will overcome the lesser leverage weight of the hopper door and the handle will automatically return to its neutral position and the hopper door will automatically complete its closing.

It will be recognized from the above description that the objects of the invention have been achieved by providing a double door closure having a simple but effective interlocking mechanism which is inexpensive and durable, and which insures that the inner door will be closed and locked whenever the hopper door is opened.

While in accordance with the patent statutes, one best known embodiment of my invention has been described herein, it is to be specifically understood that I am not to be limited thereto or thereby, but that the scope of my invention is defined in the appended claims.

I claim:

1. An intake door for rubbish chute or the like comprising a rectangular frame adapted to be mounted in association with the side of the chute, a rectangular hood secured to the inner edge of the top and sides of the frame and extending to the bottom secured to the lower edge of the frame sloping inwardly and downwardly into the chute, a hopper door hingedly secured in the frame along the lower edge thereof, a baffle door

hingedly secured along its upper edge to the hood in spaced-apart relation to the hopper door, manually operated means for operatively interlocking the doors including a circular cam plate rotatably supported on a shaft through its center, said cam plate having arcuate slots in diametrically opposed relationship adjacent the peripheral edge thereof, a handle secured to the cam plate for manually rotating the cam plate, a crank arm secured to the hopper door, a link pivotally secured to the crank arm at one end and slidably engaging one cam plate slot at the other end, a second crank arm secured to the baffle door, a second link pivotally secured to a second crank arm at one end and slidably engaging the second cam plate slot at the other end, a spring secured to the hopper door and anchored to the frame for urging the door into closed position, a locking link pivotally secured to the second crank arm, said link having a notch releasably engaging the cam plate shaft when the baffle door is in closed position, and a pin adjacent the peripheral edge of the cam plate and secured thereto adapted to engage and move the locking link automatically when the cam plate is rotated in a direction to open the baffle door to thereby disengage the notch from the shaft.

2. A double door closure of the type described comprising two doors hingedly supported in spaced-apart relationship, an enclosing frame in association with the two doors adapted to form a closed passage between the doors, an interlocking closure assembly which permits only one door to be opened at a time including a plate rotatably secured to the frame, means for rotating the plate, crank means operatively associated with each door and engaging said plate whereby rotation of the plate in one direction opens one door and rotation in the opposite direction opens the other door, a locking link pivotally carried by one of said crank means, and a pin on said plate for engaging said locking link to lock one door in closed position and being disengageable automatically by movement of said plate in one direction.

3. An intake door assembly for a rubbish chute or the like and including a box-like hood, a baffle door hinged along its upper edge adjacent the top and back of the hood, a closure door hinged along its bottom edge adjacent the bottom and front of the hood, a crank arm secured to the baffle door, a crank arm secured to the closure door, both crank arms being positioned to the side of the hood, a single operating lever extending beyond the front of the closure door and positioned to the side of the hood between the crank arms, oppositely-acting, lost-motion connections between each crank arm and the lever, resilient means holding one door closed when its lost-motion connection is operating, and locking linkage controlled by the lever for holding the other door closed when its lost-motion connection is operating.

4. An intake door for a rubbish chute, or the like comprising a frame, a hopper door hingedly

5
10
15
20

secured in the frame along the lower edge thereof, a baffle door hingedly secured along its upper edge to the hood in spaced-apart relation to the hopper door, manually operated means for operatively interlocking the doors including a circular cam plate, a shaft rotatably supporting said cam plate on said frame, said cam plate having arcuate slots in diametrically opposed relationship adjacent the peripheral edge thereof, a handle secured to the cam plate for manually rotating the cam plate, a crank arm secured to the hopper door, a link pivotally secured to the crank arm at one end and slidably engaging one cam plate slot at the other end, a second crank arm secured to the baffle door, a second link pivotally secured to a second crank arm at one end and slidably engaging the second cam plate slot at the other end, pin means carried by said cam plate, and a locking link pivotally associated with said second crank arm and having a locking notch therein engageable with said shaft for continuously engaging said shaft when said hopper door is open whereby the baffle door is locked in closed position when the cam plate is rotated to open the hopper door, said pin means being positioned at the top of said cam plate when it is at a neutral position with both said doors closed, said pin means disengaging said locking link and shaft with initial movement of said cam plate for opening said baffle door.

5. Door operating mechanism and the like including a circular cam plate rotatably supported on a shaft through its center, the cam plate having arcuate slots in opposed relationship adjacent the peripheral edge thereof, a handle secured to the cam plate for manually rotating the cam plate, a pivotally mounted crank arm, a link pivotally secured to the crank arm at one end and slidably engaging one cam plate slot at the other end, a second pivotally mounted crank arm, a second link pivotally secured to the second crank arm at one end and slidably engaging the second cam plate slot at the other end, a spring secured to one crank arm for holding it resiliently in one direction, and locking means operatively associated with the other crank arm and releasably engaging the cam plate whereby the second crank arm is locked in one position when the cam plate is rotated to move the other crank arm against the action of the spring, the locking means being automatically released when the cam plate is rotated in the opposite direction.
